UNITED STATES PATENT OFFICE.

MAX F. MANGELSDORFF, OF UNION HILL, NEW JERSEY.

PROCESS FOR THE PREVENTION OF ADHERENCE OF MOIST PARTICLES.

1,400,176

Specification of Letters Patent. Patented Dec. 13, 1921.

Application filed September 20, 1918. Serial No. 254,900.

To all whom it may concern:

Be it known that I, MAX F. MANGELSDORFF, a citizen of the United States, residing in Union Hill, county of Hudson, and State of New Jersey, have invented certain new and useful Improvements in Processes for the Prevention of Adherence of Moist Particles, of which the following is a full, clear, and exact specification.

10 My process relates to the treatment of moist particles and refers particularly to the treatment of moist particles having a tendency to adhere to each other.

One object of my invention is a process 15 whereby moist particles may be treated to prevent the adherence of the particles during their drying.

Another object of my invention is a process 20 whereby moist particles may be so treated that they may be dried in a condition in which the particles are free from each other. Another object of my invention is a process whereby particles may be passed continuously from a steaming treatment to a drier 25 and treated to prevent the adherence of the particles during the drying.

Another object of my invention is a process 30 whereby the adhesive properties of moist particles may be rendered inactive and allow of the drying of the particle free from adherence.

These and other objects of my invention will be evident upon a consideration of my specification, claims and drawings.

35 It is frequently desirable to dry moist materials having gelatinous, starchy or similar properties in such a manner that the dried particles of the material will be separated from each other, and in order to accomplish this, it is necessary to overcome, or prevent, the action of the starchy or mucilaginous materials during the drying treatment.

40 Among the important materials to which such treatment is necessary are vegetables and fruits, the drying of which presents economic properties of the greatest value.

45 In the drying of vegetables and fruits, it is essential that none of the natural properties, or contents, be changed, in order that all of the normal food values and tasting qualities may be retained.

In explaining my process, I will refer par-

ticularly to potatoes, although my process is in no way limited to that vegetable. 55

The preferred method of drying potatoes, is to slice them, subject them to hot water or steam and then dry them in such a manner that each particle, or slice, is thoroughly dried and free from adherence to other 60 slices.

These desired results are impossible to obtain, if the potatoes are simply sliced, steamed and dried, as the starchy ingredients of the potato cause the slices to adhere to each other during the drying process, thus preventing uniform drying and presenting the dried material in masses of irregular size and shape, preventing economic packing and handling and giving 70 them an unattractive appearance.

It is to be further noted that any process to which the potatoes are subjected must be of such a character as to retain the ingredients of the vegetable in an unchanged 75 condition in order that the dried product may be equal to, and have the characteristics of, the original undried article.

The process of my invention overcomes all of the above objections and produces all of 80 the above desired results and presents a method whereby potatoes, and similar products, may be dried with the retention of all of the original properties of the products while maintaining the particles in a condition 85 free from adherence to each other.

I have found that if cool air, preferably moist, be impinged upon, or brought into contact with, the hot moist slices of the vegetable, or similar products, that the exterior surface of the particles is converted 90 into a condition which will overcome the previously existing tendency of adherence and allow the particles to be dried in a condition 95 free from each other.

The use of air instead of hot water for the purposes described in this application has valuable economic advantages among which are the fact that it obviates the necessity of hot water operation and allows 100 the particles to be continuously passed from the steaming operation to the drying chamber without manual manipulation and with a very considerable saving of time. It has a further advantage that none of the necessary ingredients of the particles are ab-

sorbed and removed by the hot water but all of these ingredients are retained within the vegetable products.

The process of my invention, therefore, 5 comprises bringing the hot moist particles into contact with cool air, the conditions of treatment and the temperature of the products and of the air being dependent upon the articles treated and the particular apparatus employed.

In the accompanying drawings, illustrating modified forms of an apparatus suitable for the carrying out of my invention, similar parts are designated by similar numerals:

Figure 1 is a diagrammatic drawing of one form of an apparatus suitable for my process.

Fig. 2 is a section through the line 2—2 of 20 Fig. 1.

Fig. 4 is a diagrammatic drawing of a modified form of an apparatus suitable for my process.

Fig. 3 is a broken detail of the belt con- 25 nveyor of Figs. 1 and 4.

The device shown in Figs. 1 and 2 comprises a treating box 10, having the chute 11, connected with the steamer 12. The chute 11 contains the revoluble delivering member 13, revoluble by means of any suitable 30 means, the wings of the member 13 having but slight clearance from the sides of the chute 11, in order to prevent the air within the box 10 from passing into the steamer 12.

35 The pipe 14 connects the delivering end of the air blower 15 with the box 10. The pipe 16 connects the box 10 with the pipe 17 which is connected to the intake end of the blower 15. The pipe 17 extends outwardly

40 into the pipes 18 and 19 which open into the atmosphere. A thermostat 20 operates the damper 21 in such a manner as to control the temperature of the air delivered by the blower 15 into the box 10. Opening into

45 the pipe 17 is the water pipe 22, having the valve 23, and carrying the sprayer, or atomizer, 24 at its lower extremity. The chute 25 connects the box 10 with a drier, not shown, and contains a revoluble delivering

50 member 26, revoluble by means of any suitable means, the wings of the member 26 having but slight clearance from the sides of the chute 25, in order to prevent the air within the box 10 from passing into the drier.

55 A water trap 27 is connected with the bottom of the box 10, and a door 28, opening into the box 10, allows of the removal of any particles that have fallen through the perforated belt.

60 Extending across the interior of the box 10, and revoluble therein, is a series of shafts 30, 30, connected with a source of revoluble power, not shown. Fixedly at-

65 tached to each shaft 30 is a cylindrical member 31. Intermediate of the shafts 30, 30

is a series of shafts 32, 32, supported by the sides of the box 10 and revoluble therein. Fixedly attached to each shaft 32 is a series of spaced annular flanges 33, 33, the diameter of the flanges 33, 33 being the same as the 70 diameter of the cylinders 31, 31. The two idler cylindrical members 34, 34 are fixedly attached to the shafts 35, 35 revolubly supported by the sides of the box 10. A chain belt 36 passes above and upon the cylinders 75 31, 31, below the flanges 33, 33 and below the idlers 34, 34, the revolution of the cylinders 31, 31 causing the belt to pass continuously over the cylinders 31, 31, under the flanges 33, 33 and under the idlers 34, 34. 80

The operation of the device is as follows, assuming that sliced potatoes are the particles to be treated:

The blower 15 is started, and water introduced through the pipe 22 and the sprayer 85 24. The delivering member 13 is revolved, feeding the sliced potatoes through the chute 11 into the box 10, upon the chain belt 36 which carries the particles across the box 10 and delivers them into the chute 25, whence 90 they are delivered into the drier by means of the delivering member 26.

The rapidity of the movement of the particles through the chute 11 is equal to the rapidity of the movement of the particles 95 through the chute 25, this rapidity of movement being governed by the speed of revolution of the delivering members 13 and 26 respectively. As the particles pass down the chute 11, the cool moist air passing through 100 the pipe 14 is impinged directly upon them, the action of cool moist air being maintained throughout their passage through the box 10. When the temperature of the air passing through the pipe 17 is greater than the 105 desired temperature, the thermostat 20 moves the damper 21, closing off the pipe 17, thus causing a greater proportion of cool air to enter through the pipe 19. When the temperature of the air passing through the 110 pipe 17 is less than the required temperature, the thermostat will move the damper 21, closing off the pipe 19, thus reducing the amount of cool air drawn through the pipe 19 and increasing the amount of warm air 115 drawn from the pipe 16.

In the modification of the device, shown in Fig. 4, the cool moist air passes through the pipe 14 and is brought into contact with the particles upon belt 36, after they have 120 traversed the length of the box 10, the particles thus being somewhat reduced in temperature from that of entrance into the box 10, before they are treated with the cool moist air delivered by the pump 15.

125 From the above description, it is seen that in my process of treating hot moist particles, the temperature of said particles is suddenly reduced by means of cool air before their entrance into the drying chamber.

I do not limit myself to the particular method described, nor to the particular apparatus shown and described, both of which may be varied without going beyond the 5 scope of my invention.

What I claim is:—

1. The process of producing dry inadhering vegetable particles which comprises heating the particles in the presence of a 10 moist medium, subjecting the heating particles to the action of a current of cool moist air and drying the particles.

2. The process of producing dry inadhering vegetable particles which comprises heating the particles in the presence of 15 water, removing the heated particles from the volume of water, subjecting the heated particles to the action of a current of cool moist air and drying the cooled particles.

Signed at Albion, in the county of Orleans 20 and State of New York this 17th day of September, 1918.

MAX F. MANGELSDORFF.
